Atty.

UNITED STATES PATENT OFFICE.

EINAR NEERUP, OF CHICAGO, ILLINOIS.

HYDROMETER-SYRINGE.

1,384,399.

Specification of Letters Patent. Patented July 12, 1921.

Application filed November 1, 1920. Serial No. 420,969.

To all whom it may concern:

Be it known that I, EINAR NEERUP, a citizen of the United States of America, and a resident of Chicago, in the county of Cook,

5 State of Illinois, have invented certain new and useful Improvements in Hydrometer-Syringes, of which the following is a specification.

This invention relates to hydrometer 10 syringes or chargometers employed in testing the specific gravity of the acid charges of storage batteries and the like uses, and the present improvement has for its object:—

To provide a structural formation and association of parts wherein a substantial and effective connection is attained between the transparent view cylinder and the suction bulb and the inlet-outlet neck or tube of the appliance, and with which a choking of said 15 inlet-outlet passage by the lower end of the hydrometer, is effectively prevented, all as will hereinafter more fully appear.

In the accompanying drawings:—

Figure 1, is a side elevation illustrating 20 the general arrangement of parts in the present invention.

Fig. 2, is an enlarged central section of the upper portion of the appliance.

Fig. 3, is a similar view of the lower portion of the appliance.

Fig. 4, is a horizontal section on line 4—4 Fig. 3.

Like reference numerals indicate like parts in the several views.

35 Referring to the drawing, 1 designates the hollow cylindrical casing of the appliance, formed of glass or like transparent material and provided with annular beads or enlargements 2 at its respective ends.

40 3 designates a hydrometer arranged for vertical movement within the casing 1, as usual in the present class of appliances.

45 4 designates the upper or suction head of the appliance, usually of the ordinary rubber bulb type shown and which in the present improvement is connected to the upper end of the casing 1 by a construction as follows:—

50 5 designates the body portion of an upper cap piece of rubber or like elastic material, formed with a central orifice for the reception of the connecting nipple hereinafter described, and having a depending skirt portion 7 adapted to embrace the upper end of the transparent casing 1.

55 8 designates an annular recess formed at

the upper end of the cavity of the aforesaid skirt portion 7 for the reception of and engagement with the upper bead or enlargement 2 of the casing 1 aforesaid.

60 9 designates an upwardly extending circular rim forming an integral part of the body portion 5 of the upper cap piece, with its cavity adapted to receive the lower end or neck of the suction bulb 4 as illustrated in Fig. 4.

65 10 designates the tubular shank of a connecting nipple adapted to fit the central orifice 6 aforesaid, and having at its lower end an annular stop flange 11 and at its upper end an enlargement 12, preferably of the pear shape shown in Fig. 2, for engagement in the bore of the lower end portion or neck of the suction bulb 4.

70 13 designates the body portion of a lower cap piece of rubber or like elastic material, formed with a central inlet-outlet passage and having an upwardly extending skirt portion 14 adapted to embrace the lower end of the transparent casing 1.

75 15 designates an annular recess formed at the lower end of the cavity of the aforesaid skirt portion 14 for the reception of and engagement with the lower bead or enlargement 2 of the casing 1, aforesaid.

80 16 designates a plurality of radial ribs formed on the upper surface of the body portion 13 of the lower cap piece, in adjacent relation to the inlet-outlet passage of the same, and adapted to provide abutments for 90 the lower end of the hydrometer 3 and prevent the same from covering and choking said inlet-outlet passage.

85 17 designates a tubular extension or neck on the aforesaid lower cap piece, adapted for 95 insertion in the liquid to be tested and provide for a ready introduction of the liquid into the transparent view cylinder 1 in the operation of attaining a hydrometric reading of the specific gravity of the liquid.

100 Having thus fully described my said invention what I claim as new and desire to secure by Letters Patent is:—

1. In a hydrometer syringe, the combination of a transparent view casing having a 105 marginal bead at top, a cap piece of elastic material formed with a skirt portion and with an annular recess at the upper end of the cavity of the skirt portion for engagement with the upper beaded end of the view 110 casing, suction means consisting of an elastic hollow bulb, and a connecting means be-

tween said cap piece and bulb comprising a nipple having a shank portion, a bottom flange and an expanded top portion.

2. In a hydrometer syringe, the combination of a transparent view casing having a 5 marginal bead at top, a cap piece of elastic material formed with a skirt portion and with an annular recess at the upper end of the cavity of the skirt portion for engagement with the upper beaded end of the view

casing, suction means consisting of an elastic hollow bulb, and connecting means between said cap piece and bulb comprising a nipple having a shank portion, a hollow flange and an expanded top portion, the cap piece having an annular rim at top adapted to inclose the lower end of said bulb. 15

Signed at Chicago, Illinois, this 29th day of October, 1920.

EINAR NEERUP.
